DESIGN FOR A LEAD PENCIL

Isidor Chesler, West Orange, N. J., assignor to
Eagle Pencil Company, New York, N. Y., a cor-
poration of Delaware

Application April 29, 1936, Serial No. 62,369

Term of patent 14 years

To all whom it may concern:

Be it known that I, Isidor Chesler, a citizen
of the United States of America, residing at 28
Oxford Terrace, West Orange, New Jersey, have
invented a new, original, and ornamental Design
for a Lead Pencil, of which the following is a
specification, reference being had to the accom-
panying drawing, forming part thereof.

Fig. 1 is a top plan view of a lead pencil show-
ing my new design;

Fig. 2 is a side elevational view; and
Fig. 3 is an enlarged transverse sectional view
disclosing the outline of the shell of the pencil.

I claim:

The ornamental design for a lead pencil, as
shown.

ISIDOR CHESLER.
